UNITED STATES PATENT OFFICE.

GUY C. MITCHELL, OF HAMILTON, OHIO, ASSIGNOR TO THE HOOVEN, OWENS, RENT-SCHLER COMPANY, OF HAMILTON, OHIO, A CORPORATION OF OHIO.

HYDRAULIC BEARING FOR SUGAR MILLS AND THE LIKE.

Application filed October 25, 1920. Serial No. 419,550.

To all whom it may concern:

Be it known that I, GUY C. MITCHELL, a citizen of the United States of America, residing at Hamilton, in the county of 5 Butler and State of Ohio, have invented certain new and useful Improvements in Hydraulic Bearings for Sugar Mills and the like, of which the following is a full, clear, and exact description.

10 This invention relates to hydraulic pressure gear for mill rolls, and more particularly to hydraulic pressure regulating mechanism adapted for use in connection with mills for expressing juice from sugar cane.

15 One of the principal objects of the invention is to provide pressure regulating mechanism adapted to permit variation in the distance separating the surfaces of the rolls to allow varying thicknesses of material to 20 pass between them while still maintaining constant the pressure on the material.

25 Another object of the invention is to provide an improved construction which lends itself to ease of assembly, simplicity in operation and inexpensive maintenance.

Other objects of the invention will be apparent from the description set out below when taken in connection with the accompanying drawing.

30 In the drawing, in which like characters of reference designate like parts throughout the several views thereof,

Fig. 1 is a sectional view through the upper part of a roll housing embodying the 35 invention; and

Fig. 2 is a plan view of the apparatus shown in Fig. 1.

For purposes of description this invention is shown in connection with a roll 40 constituting the upper roll of a sugar mill, and since sugar mills of this type are well-known only so much of the mill structure is illustrated as is necessary for showing the construction and operation of the pressure regulator forming the subject of this 45 invention.

In the drawing, 10 designates the upper portion of the mill housing. This housing supports a lower bearing member 11 having 50 a lining 12 of any suitable material. Co-operating with the lower bearing member is an upper bearing member 13, the roll shaft 14 being journaled between said bearing members.

Mounted upon the upper end of the housing 10 is the top cap 20 which is held in properly assembled position upon the housing by means of king bolts 21, the lower ends of which are suitably attached to the housing; and the upper ends, which pass through ported plates 22 cooperating with the top cap 20, are threaded. Suitable nuts 23 are threadedly mounted on the upper ends of these bolts, for drawing the top cap tightly upon the roll housing. 55

The top cap 20 has centrally formed therein a cylinder aperture which has a lower zone 25 and an upper zone 26 of greater diameter than the lower zone; the cylinder aperture, because of these two 70 zones of different diameter, having a shoulder 27 substantially midway of its length. Preferably the lower zone 25 is provided with a removable lining 28, of suitable material, which may be readily replaced if 75 excessive wear occurs during operation of the device. When such a lining is used its upper end preferably terminates in such position as to constitute in effect a part, or continuation, of the shoulder 27. Adjacent its lower end the lower zone 25 is provided with an inturned shoulder 29.

80 Mounted within the lower zone 25 is a lower plunger 35, the lower part of the plunger extending through the aperture defined by the shoulder 29 and bearing against a toe plate 36 which in turn bears against the pressure plate 37. The pressure plate 37 cooperates with the upper bearing member 13, a gasket 38 preferably being interposed between these members. The lower plunger has a shoulder thereon adapted to cooperate with the shoulder 29 to limit movement of the plunger toward the pressure member; that is, its movement in one 95 direction is limited, thus preventing the exerting of excessive pressure on the bearing members.

Within the cylinder aperture is an upper plunger 40, said plunger having its lower 100 part adapted for location within the lower zone 25 and its upper part adapted for location within the upper zone 26, the plunger being thus provided, in effect, with a shoulder 41 adapted to cooperate with the shoulder 27 to limit movement of the plunger in 105 a downward direction.

Carried by the wall of the upper zone

2
of the cylinder aperture are a plurality of spaced locking lugs 45, the diameter of the passage between opposing lugs being greater than the greatest diameter of the 5 lower plunger 35, the upper plunger 40 and the lining member 28, to permit of ready insertion, or removal of these parts from the cylinder aperture. Mounted within the upper zone 26 is a cross-block 46 having a 10 plurality of lugs 47, carried thereby, which lugs are adapted, when the cross-block is in one position, to pass through the spaces between the locking lugs 45, and when turned into another position to cooperate with the 15 lower faces of the locking lugs to limit movement of the upper plunger 40 against movement in the other direction, that is away from the shoulder 27.

Opening into the cylinder aperture, between the upper and lower plungers is a 20 pipe 50 through which any desired pressure fluid is introduced. The opposing faces of the upper and lower plungers, that is the faces which are subjected to the pressure fluid, are provided each with a suitable packing 55, which packing is preferably in the form of a cup leather. Associated with each packing is a follower plate 56, each plate being adapted to hold its cooperating 25 packing in position, when the device is assembled. A spring 57 is located between the two follower plates, and holds these plates, with their cooperating packings against the plungers. This construction obviates the use of bolts, and corresponding 30 holes in the packings, for holding these packings in position.

A cover plate 60 is provided, which closes the upper end of the cylinder aperture. 40 Threaded openings, designated generally by the numeral 61, are provided in the various removable parts of the apparatus for receiving a suitable tool, to facilitate handling of these parts.

45 As stated above, this pressure regulating mechanism is adapted to permit movement of the roll carried upon the roll shaft 14, relative to its cooperating roll or rolls, in order to allow passage of a varying quantity of material between these rolls, while maintaining constant the pressure exerted upon that material. The device is therefor, so arranged that movement of the lower plunger 50 toward the upper bearing member 13 is 55 limited, although movement of this plunger in the opposite direction can take place if it is subjected to a pressure greater than exists within the cylinder aperture between two plungers, through the pipe 50. The 60 pressures used in actual practice will vary within quite wide limits according to the character of material passing between the rolls, and also according to the size of the rolls. When sugar cane is being crushed 65 the general practice is to exert upon the cane

as it passes between the rolls, pressures varying from one hundred and seventy-five to five hundred tons.

This pressure fluid forces the upper plunger 40 against the cross-block 46, and forces 70 the lower plunger 35 against the stop shoulder 29. As material passes between the roll, the upper roll will be lifted, carrying with it the upper bearing member 13, the pressure plate 37 and the toe plate 36 75 into contact with the end of the lower plunger 35. If more material passes between the rolls, thus tending to spread them apart, further movement of the roll can take place without any increase in pressure above that 80 existing within the cylinder aperture.

While the form of apparatus herein shown and described constitutes a preferred form of embodiment of the invention, it is to be understood that other forms of embodiment might be adopted, all coming 85 within the scope of the claims which follow.

What I claim is:

1. In a device of the character described, a top cap having an aperture therein constituting a cylinder, an inturned shoulder in the lower end of said cylinder, locking lugs in the upper end of said cylinder, a lower plunger adapted for positioning within said cylinder, means thereon adapted to cooperate 90 with said inturned shoulder to limit movement of said plunger in one direction; an upper plunger adapted for positioning within said cylinder, a cross-block constructed for positioning within said cylinder, lugs thereon adapted to cooperate with said locking lugs to limit movement of said upper plunger in one direction; and means for admitting 95 pressure fluid to said cylinder, between said plungers.

2. In a device of the character described, a top cap having an aperture extending therethrough constituting a cylinder, comprising a lower zone, and an upper zone of greater diameter than said lower zone; an in-turned shoulder within the lower zone; locking lugs within the upper zone; a plunger within the lower zone, a shoulder thereon adapted to cooperate with said inturned shoulder to limit movement thereof; an upper plunger within said upper zone; a shoulder on said upper plunger, means within the cylinder, cooperating with the shoulder on said upper plunger, for limiting movement of said upper plunger in one direction; a cross-block within the upper zone, lugs thereon adapted to cooperate with said locking lugs to hold said cross-block within said upper zone; said cross-block being adapted to limit movement of the upper 110 plunger in the other direction; and means for admitting pressure fluid to said cylinder between the plungers.

3. In a device of the character described, a top cap having an aperture extending 115

therethrough and constituting a cylinder, said cylinder comprising a lower zone, and an upper zone of greater diameter than said lower zone; a lining within said lower zone, 5 the upper end of said lining constituting a shoulder within the cylinder; locking lugs within the upper zone, the effective opening between said lugs being greater than the diameter of the lower zone and of the upper 10 plunger; a plunger within the lower zone, a shoulder thereon adapted to cooperate with said inturned shoulder to limit movement of said plunger in one direction; an upper plunger within said upper zone, a shoulder 15 thereon adapted to cooperate with the upper end of the lining within said lower zone, to limit movement of said upper plunger in one direction; a cross-block within the upper zone, lugs thereon adapted to cooperate with 20 the locking lugs in the upper zone to hold said cross-block within said upper zone to

limit movement of the upper plunger in the other direction; and means for admitting pressure fluid to said cylinder aperture between the plunger. 25

4. In a device of the character described, a top cap having an aperture extending therethrough constituting a cylinder, opposed plungers within said cylinder; packing members associated with the adjacent 30 faces of the opposed plungers; a follower plate cooperating with each packing member; and a spring between the follower plates adapted to urge said plates to hold each of the packing members cooperating therewith 35 against its associated plunger; the construction being such that each packing member is held in position without the use of bolts and corresponding holes within the packing.

In testimony whereof I hereto affix my signature.

GUY C. MITCHELL.
